COMBINED BATHHOUSE AND LAUNDRY BUILDING FOR CAMPGROUNDS

Charles W. Brady, 909 Cherry St.,
Columbia, Mo. 65201

Filed Sept. 16, 1969, Ser. No. 19,174

Term of patent 14 years

Int. Cl. D25—04

U.S. CL. D13—1

Fig. 1

Fig. 2

Fig. 3

FIG. 1 is a perspective view of said combined bathhouse and laundry building for campgrounds showing my new design.

FIG. 2 is a side elevation of said building as seen from each side thereof.

FIG. 3 is an end elevation of said building as seen from each end thereof.

The flat conventional platforms, as seen in FIG. 1 have been omitted from FIGS. 2 and 3, but are understood to be a part of the claim.

I claim:

The ornamental design for a combined bathhouse and laundry building for campgrounds, as shown and described.
